Primary Examiner — Keith J Wilson*(74) Attorney, Agent, or Firm* — Buchanan Ingersoll & Rooney PC(57) **CLAIM**

The ornamental design for a nozzle unit as shown and described.

DESCRIPTION

FIG. 1 is a perspective view of an embodiment of a nozzle unit showing my new design;

FIG. 2 is a top view thereof;

FIG. 3 is a front side view thereof;

FIG. 4 is a rear side view thereof;

FIG. 5 is a left side view thereof;

FIG. 6 is a right side view thereof; and,

FIG. 7 is a bottom view thereof.

The broken lines shown in the drawings represent portions of the nozzle device that form no part of the claimed design.

1 Claim, 7 Drawing Sheets## Related U.S. Application Data

application No. 17/375,073, filed on Jul. 14, 2021, now Pat. No. 11,772,107, and a continuation of application No. 29/796,856, filed on Jun. 28, 2021, now Pat. No. Des. 1,026,168, which is a continuation of application No. 15/741,905, filed as application No. PCT/EP2016/065936 on Jul. 6, 2016, now Pat. No. 11,090,665, said application No. 17/375,073 is a continuation of application No. 15/741,905, filed as application No. PCT/EP2016/065936 on Jul. 6, 2016, now Pat. No. 11,090,665.
